UNITED STATES PATENT OFFICE.

WILLIAM HARRIS, OF SLOCAN CITY, BRITISH COLUMBIA, CANADA.

GATE FOR RAILWAY CROSSINGS OR THE LIKE.

Application filed October 20, 1921. Serial No. 509,070.

To all whom it may concern:

Be it known that I, WILLIAM HARRIS, a subject of the King of Great Britain, residing at Slocan City, Province of British Columbia, Canada, have invented certain new and useful Improvements in Gates for Railway Crossings or the like; and I do hereby declare that the following is a full, clear, and exact description of the invention, 10 such as will enable others skilled in the art to which it appertains to make and use the same.

The present invention relates to new and useful improvements in gates or closures 15 and more particularly to a device of the class described which is preferably applicable to railway crossings or the like, wherein the tracks pass through fences or other inclosures, and has for its principal object 20 the provision of a gate which will be automatically closed when a person or animal crosses the track adjacent the opening in the inclosure through which the track passes.

A further object of the invention is the 25 provision of a gate or the like, such as above referred to, which will be comparatively simple and inexpensive to manufacture, reliable and efficient in use, and readily operated.

30 With the above and other objects in view, the present invention resides in the novel features of construction, formations, combinations and arrangements of parts to be hereinafter more fully described, claimed, 35 and illustrated in the accompanying drawings forming a part of the present application and in which:

Figure 1 is a plan view of the invention applied to a roadway and the intersecting 40 track of a railway;

Figure 2 is a plan view of one of the gate sections removed;

Figure 3 is a side view thereof showing the gate in its lowermost position;

45 Figure 4 is a similar view showing the gate raised;

Figure 5 is a detail view illustrating the manner of adjusting one of the walls; and,

50 Figure 6 is a perspective view of one of the arms with the weight applied thereto.

Referring now to the accompanying drawings by corresponding characters of reference throughout the several views, the numeral 5 designates a roadway which is

55 crossed by the rails 6 of a railway track 7. Suitable inclosures 8 are provided upon

opposite sides of the roadway 5 through which the roadway track 7 passes through suitable openings 9 provided therein and which are designed to be closed by the 60 hinged gates or closures 10. As the closures 10 upon opposite sides of the track are identical in formation, a detailed description of but one is deemed necessary. The rails 6 are mounted upon the usual ties 11, 12, 13 and 14 upon opposite sides of the roadway. Operating platforms 15 are disposed between the ties 11 and 12 and are journaled upon the rods 16 at their inner ends which rods are rotatably mounted in the outer 70 ends of straps 17 which are secured to the upper sides of the ties 11. The plates 15 are mounted upon suitable straps 18 secured to the underside thereof and which are arranged for vertical movement in the cut 75 away portions 19 of the intermediate ties 20 disposed between the first mentioned ties 11 and 12. A shaft 21 is journaled upon the inner side of each of the ties 12 in suitable straps 22 and has formed thereon or secured 80 thereto in any manner rigid arms 23 which project inwardly and are journaled on the shaft 24 carried by the outer edges of the plates or platforms 15. Obviously upon the depression of these plates or platforms 15, 85 the shaft 21 will be rotated causing the swinging movement of the outer bell cranks 25 which are secured thereto. These bell cranks 25 are attached by links 26 to the upwardly inclined arms 27 which are secured to the shafts 28 journaled in suitable straps 29 upon the outer sides of the ties 13. The shafts 28 have rigidly secured thereto straps 30 which are secured to the underside of the gates or swinging closures 10, and 90 obviously upon the upward movement of the arms 27 caused by the depression of the platform 15, the gates 10 will be raised from the position shown in Figure 3 to that shown in Figure 4, thus closing the openings 9 in the inclosures 8. The shafts 28 have journaled thereon suitable arms 31 provided with adjustable weights 32. The inner ends of these arms 31 are offset as at 33 to contact with the arms 27 so that when 100 the gates are in their raised position and pressure is removed from the plates or platforms 15, these weighted arms will return the gates to their lowermost positions.

From the foregoing description, taken in 110 connection with the accompanying drawings, it will be manifest that a gate for

railways and the like is provided which will fulfil all of the necessary requirements of such a device, and it should be understood in this connection that various minor changes in the specific details of construction can be resorted to within the scope of the appended claim, without departing from the spirit or sacrificing any of the advantages of the invention.

Having thus fully described the invention, what I claim as new and desire to protect by Letters Patent is:—

The herein described apparatus comprising a depressible platform, a shaft rotatably connected to the depressible platform for rotation upon the downward move-

ment of said platform, a lever keyed to the shaft and connected with said platform, a second shaft rotatably mounted in spaced parallel relation with the first mentioned shaft, an arm extending from the second shaft, to the lever of the first mentioned shaft, a gate secured to the second mentioned shaft, an arm journaled upon the second mentioned shaft, a stop carried by said arm and engaging the first mentioned arm carried by the said shaft, and a weight adjustable upon said arm, substantially as and for the purposes set forth.

In witness whereof I have hereunto set my hand.

WILLIAM HARRIS.
